UNITED STATES PATENT OFFICE.

STEPHEN J. VAN KUREN, OF CEDAR RAPIDS, IOWA, ASSIGNOR TO J. G. CHERRY COMPANY, OF CEDAR RAPIDS, IOWA, A CORPORATION OF IOWA.

CHURN-TIMER.

1,371,454.

Specification of Letters Patent. Patented Mar. 15, 1921.

Application filed May 31, 1919. Serial No. 300,902.

To all whom it may concern:

Be it known that I, STEPHEN J. VAN KUREN, a citizen of the United States, residing at Cedar Rapids, in the county of Linn 5 and State of Iowa, have invented certain new and useful Improvements in Churn-Timers, of which the following is a specification.

This invention relates to timing devices 10 and it is especially designed and adapted for use in connection with churning to give a signal which will indicate to the operator when the butter working process is completed.

15 It is customary for the operator to time the butter working process by the revolutions of the churn drum, which operates at a comparatively low rate of speed, say about six revolutions per minute, when working 20 butter.

The object of this invention is to provide a timing device which can be set to give a signal after a predetermined number of revolutions of the drum so that the operator 25 may be occupied in other duties during the butter working process, knowing that he will receive ample warning from the timing device as the working process approaches completion.

30 The object of the invention is to provide a timing device without delicate or complicated parts but having a strong and substantial construction suitable for the conditions under which a butter working process 35 must necessarily be conducted with the working parts disposed in convenient position for any attention they may require.

In the accompanying drawings

Figure 1 is a top view;

40 Fig. 2 is a front elevation, and

Fig. 3 is a side view of a timing device embodying the invention.

The device comprises a rock shaft 4 mounted in bearings 5 in a suitable support 6. A rocker 7 rigidly secured on the rock shaft carries a feed pawl 8 which is adapted to engage the teeth peripherally disposed on the face of a dial plate 9 revolubly secured by a bolt 10 to the support.

50 A spring 11 on the bolt 10 is interposed between the dial plate and the arm 6' of the support to hold the dial plate in place. A spring 12 is arranged between a lug 13

on the rocker 7 and the support to normally hold the rocker and the feed pawl in elevated position and to return the parts to this position after each feeding operation. A spring 14 is connected to a lug 15 on the feed pawl and to a lug 16 on the rocker to hold the pawl 17 in operative relation to the dial plate. A holding pawl 17 is pivotally mounted on the arm 6'' of the support and is held in operative engagement with the dial plate by a spring 18. A tripper 19 of any suitable construction is rigidly mounted on one or the other end of the rock shaft and its outer free end is arranged to be engaged and operated by some moving part to rock the shaft and cause the feed pawl to revolve the dial plate the distance of one tooth.

The teeth of the dial plate are numbered clockwise and an index pointer 20 is rigidly fastened to the arm 6' of the support and is conveniently directed downward in adjacent 75 relation to the teeth of the dial plate. An alarm bell 21 is mounted on the support and a cam 22 on the face of the dial plate is arranged to travel with the dial plate beneath the plunger or other operating member 23 of the bell to sound an alarm. This bell may be of any suitable type but I prefer to provide a continuous ringing bell and to make the cam of such length that it will engage the bell-operating member and continue to sound an alarm during a plurality of revolutions of the churn so that ample warning of the completion of the butter working process will be given.

In practice the device is mounted on the 90 leg or standard of a churn at either end thereof, or in any suitable position where the tripper 19 is adapted to be engaged and operated by a cam or other suitable device on the revolving drum of the churn. The operator will set the dial plate by turning it clockwise until the tooth representing the predetermined number of revolutions desired is disposed opposite the pointer 20. Then the churn is placed in operation and 100 each time the tripper 19 is tripped the feed pawl will advance the dial plate the distance of a tooth and the holding pawl will hold it in this position. The spring 11 exerts sufficient tension on the dial plate to 105 prevent it from turning freely and yet per-

mitting it to be revolved by hand or by the feed pawl. As the butter working process nears completion the cam 22 will be carried into operative engagement with the bell operating member 23 and sound an alarm, this alarm being continued as long as the cam continues in operative engagement with said member and preferably during several revolutions of the churn so that the operator 10 will have ample opportunity to leave any other work upon which he may be engaged to resume his attention to the churn.

When it is desired to render the device inoperative for any reason the shaft may be 15 rocked to the limit of its movement, or at least until the tripper is out of operative position, and the hook 24 engaged with the lug 25 on the rocker 7 to hold the parts in this position. While the invention is particularly intended for use in connection with 20 churning for timing the butter working process it can obviously be employed for many other purposes which will be readily suggested to those skilled in the art.

I have shown the device in full lines as constructed for a right hand churn, in which the operating devices are located at the right end of the churn. To apply the device to a left hand churn, in which the operating devices are located at the left end of the churn, it is only necessary to remove the tripper 19 and apply to the other end of the shaft a similarly constructed tripper 19' as shown in dotted lines.

My improved device is strong and substantial in construction, it has no delicate or complicated mechanism which would soon become corroded and disordered under the moist conditions which prevail in creameries, it can be easily applied to a churn, and it can be readily adjusted for operation. Instead of mounting the device on a fixed part to be operated by a moving part on the drum of the churn the device may be mounted on 45 the drum of the churn to be revolved therewith and the tripper arranged to engage a fixed part, if desired.

I am aware that changes in the form and proportion of parts and in the details of 50 construction of the invention may be made without departing from the spirit or sacrificing the advantages thereof, and I therefore reserve the right to make all such changes as fairly fall within the scope of 55 the appended claims. For example, it is apparent that the cam 22 may be employed to close an electric circuit which will ring a bell or a buzzer, or flash a light, and produce any other kind of a sound or signal 60 suitable for the purpose, it being necessary only to provide a member which will be actuated by the cam for this purpose.

I claim:

1. A timing device of the character described comprising a support, a toothed dial

plate revolubly mounted on the support, means for advancing the dial plate a tooth at a time, a signal device capable of prolonged operation and a cam on the dial plate for imparting a prolonged operation to said 70 signal device.

2. A timing device of the character described comprising a support, a dial plate revolubly mounted on the support, and having teeth peripherally disposed on its face, 75 a feed pawl overhanging the face of said dial plate to engage the teeth and advance the plate a tooth at a time, a holding pawl to prevent reverse movement of the dial plate, means for operating said feed pawl, a 80 signal device capable of prolonged operation, and a cam on the face of the dial plate for imparting a prolonged operation to said signal device.

3. A timing device of the character described comprising a support, a rock shaft, 85 a tripper on the shaft adapted to be actuated to rock said shaft, a toothed dial plate revolubly mounted on the support, a rocker on said shaft, a feed pawl pivotally mounted 90 on said rocker and adapted to engage said dial plate to revolve the same a tooth at a time, a signal device, capable of prolonged operation, and a cam on the face of the dial plate for imparting a prolonged operation 95 to said signal device.

4. A timing device of the character described comprising a support, a rock shaft journaled in the support, a tripper on the shaft adapted to be actuated to rock said 100 shaft, a rocker on said shaft, a toothed dial plate revolubly mounted on the support, a feed pawl pivotally and yieldingly mounted 105 on the rocker and adapted to advance said dial plate a tooth at a time, a holding pawl to prevent reverse movement of the dial plate, a bell, capable of prolonged operation, an operating member for the bell, and a cam on the dial plate to impart a prolonged 110 operation to said member.

5. A timing device of the character described comprising a support, a rock shaft journaled in bearings in the support, a tripper on the shaft adapted to be actuated to rock said shaft, a rocker rigid on the shaft, 115 a spring for holding said rocker normally in elevated position, a toothed dial plate revolubly mounted on the support, a spring-pressed feed pawl pivotally mounted on the rocker and arranged to engage and advance 120 the dial plate a tooth at a time, a signal bell mounted on the support and capable of prolonged operation, an operating member for said bell, a cam on the face of the dial plate for imparting a prolonged operation to said 125 actuating member, and a spring bearing on the dial plate to restrain the movement thereof.

6. A timing device of the character described comprising a support, a rock shaft 130

journaled in bearings in the support, a tripper on said rock shaft adapted to be operated to rock the shaft, a rocker on said shaft, a toothed dial plate revolvably mounted on the support, a feed pawl on said rocker to advance the dial plate a tooth at a time, a signal device, capable of prolonged operation, a cam on the dial plate for imparting a prolonged operation to said signal device, a lug on the rocker, and a hook on the support adapted to be engaged with said lug to hold said tripper out of operative position.
